UNITED STATES PATENT OFFICE.

ANTON J. UPHUS, OF SEATTLE, WASHINGTON.

FOLDING TABLE.

Application filed January 9, 1922. Serial No. 527,993.

To all whom it may concern:

Be it known that I, ANTON J. UPHUS, a citizen of the United States of America, and resident of the city of Seattle, in the county of King and State of Washington, have invented certain new and useful Improvements in Folding Tables, of which the following is a specification.

My invention relates to folding tables and table-like structures, such as ironing boards which normally are folded up into a vertical position within a casing or against a wall, and which when in use are swung downward into a horizontal position.

The object of my invention is to provide a simple and inexpensive type of construction for such articles, which at the same time is easy to operate and which holds the table securely when it is swung down and which takes care of the same effectively when it is swung up.

The features of my invention which I believe to be new and upon which I desire to obtain a patent will be herein set forth and then particularly defined by the claims.

The accompanying drawings show my invention in the type of construction now preferred by me.

Figure 1 shows the table top in edge view and the frame therefor in vertical section, the same being shown as secured to a wall.

Figure 2 is a front or face view of the table when folded, into position against the face of the wall.

Figure 3 is a horizontal section taken through one of the side jambs of the frame, showing the manner of guiding and holding the inner end of the table.

Figure 4 is a face view of the metal trough which is used to line the channel in the jambs which receive the pivot and guide rollers of the table.

The frame in which the table is mounted consists of two side jambs 1 joined at top and bottom by bars 10. These are made of such size as to receive the table top 2 within them, said table top closing the opening much in resemblance to the action of a door. This frame is also preferably provided with a paneling as 11 which closes the rear face thereof. It is further provided with a cross bar as 12 which is located upwardly at a suitable distance from the lower end of the frame so that it acts as a stop engaging the upper surface of the inner end of the table top 2 when the

latter is swung into lowered position or that of use.

The jambs 1 in the lower portion of their inner faces are each provided with a vertically extending groove 3 which at its upper end is provided with a forward extension situated to receive the laterally projecting pin or roller as 20 carried at each side of the table top and at the inner end thereof. This slot has an enlargement 30 at its lower end extending forwardly. This slot on one of the stiles is provided with a channel 31 which extends to the front edge of the jamb. This is necessary only for the jamb at one side of the frame. The jamb at the other side of the frame may be lacking in this communicating channel 31. The purpose of this communicating channel 31 is to facilitate placing the table top in position after the frame has been completely assembled.

The grooves which receive the pivot and guide rollers 20 of the table are preferably provided with a metal lining. One of the metal troughs used is shown in Figure 4. This trough 5 is formed from a plate of rolled metal and has side walls 50 and 51 spaced to accommodate the guide roller 20. The side wall 51 near the lower end of the trough is separated from the main body and bent outward to form the curve 52 and at the other end is similarly cut to form the side extending loop 53. Each of these cut-away flanges is enough longer than the main body to properly line the lateral extensions. It is secured in place by screws or nails.

The table top 2 may be of any suitable character of construction. As illustrated in Figure 3 this is constructed by providing stiles 21 and the panel 22 which connects the stiles 21 and the end pieces thereof, the construction being analogous to that of a door except that the panel portion is at one side of the thickness.

The top is provided near its inner end with a metal fixture 43 which is provided with the lateral projection 20, preferably a roller, which fits in the groove 3 and the forward extension thereof. Two brace rods 4 are provided, one for each side of the table. The upper ends of each of these rods are pivoted to the table by pins, as 40, which are carried by plates 41 fixed to and preferably recessed into the edges of the table and near the marginal edge of the table. The pivot

plate 43 is preferably located near the upper marginal edge of the table with the pivot and guide pin 20 close to the inner and upper corners of the table. The lower ends of the 5 brace rods 4 are pivoted on the inner surface of the jambs 1 at the lower ends thereof or just above the lower end piece 10. The jambs 1 are also provided with a rabbet 13 extending from the point where the lower 10 ends of the brace rods 4 are pivoted, upwardly a sufficient distance to receive the full length of the brace rods 4 when the table is swung into the stored or upper position. This rabbet extends from the forward edge of the frame inwardly or to the rear a sufficient distance to accommodate 15 the brace rods 4.

To better support the pivot 42 upon which the lower end of the brace rod is pivoted, I 20 have provided a bar 14 which is secured to the upper face of the lower end piece 10 of the frame and which at its ends stops short of the inner face of the jambs 10, a sufficient distance to permit insertion of the brace 25 rods between its end and the inner face of the rabbet 13. The cross bar 14 preferably has the inner portion of its end surface 30 abutting against the inner face of the jambs 1. The outer portion of its end surface overlaps the rabbet 13 thus providing for the width of the bar 14, a groove into which the lower end of the brace rod 4 is placed. The pivot pin 42 may thus be supported by both 35 ends in the jamb and said bar 14.

The position of the table top when stored is indicated by the dotted line 55 which line 40 represents the surface of the table top which is up when swung down in the position of use and which is to the rear when it is stored. At the upper end of the space within the frame, stops as 6 are provided. These may be simple corner pieces inserted 45 in the frame. The casing thus constructed may be secured in place by the use of a lag screw 7 passing through the upper and lower cross bars 10 and other lag screws 70 which pass through the intermediate cross bar 12. All of these, or such of them as may 50 be desired, may be used. The heads of these lag screws should preferably be recessed into the cross bars as has been indicated and the recesses covered as by thin strips 8 thus giving the cross bars a finish. A similar finishing strip 80 may be employed for the

front edges of the stiles. The lag screws 7 55 and 70 may be placed at any point in the width of the casing which may be necessary in order to match with studding in the wall.

The forward enlargement 52 of the slot 3 at its lower end permits forward bodily 60 movement of the table top when it is folded up thereby making possible keeping the body of the slot toward the rear enough to accommodate the rabbets 13 in the same plane therewith and yet retain enough 65 thickness of wood between said rabbet and the slot 3. The table fulcrums on the bar 12 so that when its upper end is put in place its lower end will be brought forward, thus 70 making its outer face come true with the enclosing frame or cabinet.

This invention, as stated in the preliminary statement of invention, is applicable to tables, ironing boards and other table-like structures. I therefore desire it understood 75 that the use of the word table in the claim is intended to be construed in its broad generic meaning to cover any table-like structure, of which an ironing board is an example. 80

What I claim as my invention is:

A folded table comprising a frame having side jambs each provided in the lower part of their inner faces with a vertical guide groove located towards the rear margin thereof and having a forward extension at its upper end and a forward enlargement at its lower end, the latter enlargement having an inclined top wall, a table top adapted to fit within the frame, guiding pins laterally projecting from the inner end of the table top and fitting said grooves in the jambs, brace rods pivoted by their lower ends at the bottom outer edge of the inner faces of the jambs and by their upper ends 90 to the edges of the table top outwardly from its inner end, the inner faces of the jambs being rabbeted to receive said brace rods when the table is swung up, the frame having a cross bar connecting the side jambs 95 at a level to serve as a stop engaging the upper surface of the top when swung down and recessed back from the front faces of the jambs to permit the top to fully enter between the side jambs. 100

Signed at Seattle, King County, Washington, this 28th day of December, 1921.

ANTON J. UPHUS.
